UNITED STATES PATENT OFFICE.

JOSEPH U. HOUSEMAN, OF CHICAGO, ILLINOIS, ASSIGNOR OF ONE-HALF TO JOHN S. MOE, OF CHICAGO, ILLINOIS.

APPARATUS FOR EXHIBITING MOVING PICTURES.

1,089,219.

Specification of Letters Patent.

Patented Mar. 3, 1914.

Application filed November 4, 1912. Serial No. 729,205.

To all whom it may concern:

Be it known that I, JOSEPH U. HOUSEMAN, a citizen of the United States, residing at Chicago, in the county of Cook and State of Illinois, have invented a new and useful Improvement in Apparatus for Exhibiting Moving Pictures, of which the following is a specification.

My object is to provide certain improvements in the light-projecting features of a moving-picture exhibiting machine, with a view to rendering the pictures projected on the screen particularly clear and free from the flickering effects due to rapid changes in the intensity of the projected illuminating rays.

Referring to the accompanying drawings, which illustrate a moving-picture exhibiting machine equipped with my improvements in one desirable form—Figure 1 is a top plan and partly diagrammatic view of so much of the machine as is deemed necessary for a clear understanding of my invention; Fig. 2, an enlarged view taken from line 2 in Fig. 1 and showing my improved rotary shutter in elevation; Fig. 3, a broken and enlarged view taken from line 3 in Fig. 1 showing an auxiliary light-projecting, screen-illuminating lens and adjustable supporting means therefor; Fig. 4, a view taken from line 4 in Fig. 3; and Fig. 5, a section taken on line 5 in Fig. 4, showing, in elevation, an adjustable attachment for framing and regulating the intensity of the auxiliary screen-illuminating light-rays.

The reference numeral 6 designates a moving-picture exhibiting machine of known construction having an operating crank or handle 7 which actuates the intermittent picture-film feeding mechanism and rotates the shutter-shaft 8.

The machine is provided with the picture projecting-lens 9 and a suitable lamp-house containing an electric lamp, or other source of light, 10, and a condensing lens 11.

On the frame of the machine above the projecting-lens 9 is a horizontally-extending post 12 provided in its end with a clamping thumb-screw 13. Adjustably secured against the post 12 by the screw 13 is a supporting-bar 14. Mounted in an opening in the end of the bar 14 is a horizontal backwardly-extending rod 15 fastened in place by a set-screw 16.

The reference numeral 17 designates an auxiliary lens similar to and preferably of substantially the same power as the lens 9. Behind the lens 17 is a lamp 18 of approximately the same candle-power as the lamp 10, and in front thereof is a condenser 19 like the condenser 11. In practice, the lenses 9 and 17 are both focused upon the picture-exhibiting screen, or the like, not shown, the rays projected through the lens 9 being framed upon the screen by the usual means.

Hanging from the rod 15 between the condenser 19 and lens 17 is an attachment 20 carrying an apertured framing-slide 21 adjustable by means of a screw 22 to frame the rays from the condenser 19 through the lens 17 upon the screen in exact register with the framing of the rays from the condenser 11 through the lens 9. The attachment 20 is connected with the rod 15 by a clip 23, in which it is vertically adjustable, being secured in adjusted position by means of a thumb-screw 24.

Mounted upon the shutter shaft 8 is a rotary shutter 25. Hitherto it has been the usual practice to provide moving-picture exhibiting machines with a rotary shutter having a plurality of blades or vanes possessing a combined area equal to, or slightly exceeding, one-half the area of the shutter, the vanes being approximately equidistant apart to provide spaces between them for the passage of the rays projected from the picture projecting-lens. One of these vanes serves, in each rotation of the shutter, to cut off said rays during the feed of the film, while the other vanes serve, by multiplying the speed of the light changes upon the screen, to blend the light rays and shadows in such a way as to tone down the picture on the screen, thereby, in a measure, to neutralize the flickering effect and render the picture more steady to the eye. Any reduction of the flickering effect is thus produced at the expense of light intensity and clearness.

In my improved construction I provide a shutter 25 having a segmental opening 26, approximating from two-thirds to three-quarters of a complete circle, for the passage of the rays from the picture projecting lens 9, and a vane or blade 27, approximating from one-quarter to one-third of the circle, which cuts off the rays from the lens 9 during the feeding move-

ment of the film. At the outer side of the opening 26 is a segmental vane or blade 28 approximating from two-thirds to three-quarters of a circle, and an opening 29 diametrically opposite to and of the same relative circular extent as the vane 27, the vane 28 and opening 29 passing across the lens 17.

Mounted against the side of the attachment 20 opposite the slide 21 is a diaphanous slide 30 preferably of ground or colored glass of gradually increasing density or opaqueness from one end to the other. The slide 30 is held in the upper and lower guides 31 and is fitted at its lower edge with a rack 32, with which a thumb-operated pinion 33 on the attachment 20 meshes. The purpose of the adjustable slide 30 is to modify the light rays projected through the lens 17 so that they will equal in intensity the rays passing through the film and projected from the lens 9. Thus, in the rotation of the shutter 25, when the vane 27 passes across the lens 9, the open space 29 of the shutter passes across the lens 17, with the result that the framed portion of the screen is maintained of the same tone as the picture. By turning the pinion 33, the operator may shift the slide 30 so as to modify or intensify the light rays projected from the lens 17 against the screen, and thus equalize them with the rays projected from the lens 9. Thus, as the shutter cuts out the rays from the lens 9, it cuts in those from the lens 17, with the result that the same light-intensity is maintained throughout the framed portion of the screen, and flickering thereof is avoided.

The attachment 20 may be easily adjusted by the operator to frame the light-rays from the lens 17 upon the screen in exact register with the framing of the rays from the lens 9, thus avoiding flickering at the edges of the picture. This adjustment may be performed by sliding the bar 14 along the tightening-screw 13, swinging the attachment laterally upon the rod 15, and moving it back or forth thereon, and positioning

the slide 21 by means of the thumb-screw 22.

The shutter 25, as I prefer to construct it, is cut out of a suitable thin sheet of aluminum and is exactly balanced by applying a strip 34 of heavier metal along the edge-portion 35 outside the opening 29.

While I have shown two lamps or sources of light 10, 18, one of said lamps, more especially the lamp 18, may be replaced by a prism or other desirable form of reflector suitably positioned with reference to the lamp 10 and condenser 19 to reflect the rays of said lamp through the framing attachment 20 and lens 17 onto the screen.

The foregoing description is intended to convey a clear understanding of my improvements in what I now believe to be the best form of their embodiment, and no undue limitation should be understood therefrom. It is my intention to claim all that is novel in my invention, and that the claim shall be construed as broadly as the prior state of the art will warrant.

What I claim as new and desire to secure by Letters Patent is—

In an apparatus for exhibiting moving pictures upon a screen or the like, the combination with the intermittent feed for the film, and the picture-projecting lens, of auxiliary light-projecting means, a rotary shutter movable to shut off the picture-projecting rays during the feeding movements of the film and to direct the auxiliary light rays upon the screen during such periods, said shutter having a pair of vanes, one for each light-projecting means, said vanes being arranged at different distances from the axis of the shutter and on the same side of the axis with the vane farther from the axis having a greater length than the vane nearer the axis.

JOSEPH U. HOUSEMAN.

In the presence of—

NELLIE B. DEARBORN

OTTILIE C. AVISUS.
